Patented July 6, 1909.

UNITED STATES PATENT OFFICE.

JAMES SCHOLTZ, OF SAN FRANCISCO, CALIFORNIA.

MUSIC-SHEET TURNER.

No. 927,174.

Specification of Letters Patent.

Patented July 6, 1909.

Application filed December 10, 1908. Serial No. 466,898.

To all whom it may concern:

Be it known that I, JAMES SCHOLTZ, a citizen of the United States, residing at San Francisco, in the county of San Francisco and State of California, have invented new and useful Improvements in Music-Sheet Turners, of which the following is a specification.

The present invention relates to improvements in music sheet turners, and the object of the invention is to provide a device of this character by which the sheets can be turned by devices which are not attached to the sheets; in which the winding up of the spring mechanism will be effected automatically in the use of the apparatus; with which the piece or book of music can be readily adjusted in co-operative relation with the music turner; which can be readily adjusted for various thicknesses of the music book or piece; and which will be simple in construction and inexpensive in cost.

In the accompanying drawing, Figure 1 is a front view of the apparatus in a reduced scale; Fig. 2 is a rear view of the mechanism for operating the same; Fig. 3 is a sectional view on the line 3—3 of Fig. 2; Fig. 4 is a similar view on the line 4—4 of Fig. 3; Fig. 5 is a similar view on the line 5—5 of Fig. 2; Fig. 6 is a detail perspective view of the key strip detached; Fig. 7 is a side view of a loop.

Referring to the drawing, 1 indicates a rack which is of a general rectangular form, and comprises the side bars 2, the top bar 3 and the bottom bar 4. Said side bars are bent backward near their lower ends, as shown at 5, before being attached to the bottom bar. On the under side of the bottom bar are secured rubber blocks or feet 6 which can rest upon the rack of the piano, and in like manner, blocks 7 of rubber are secured upon the back of the top bar to rest against the front of said piano rack. Extending between the side bars 2 is an angular rest piece 8, for the sheets of music, said rest piece being connected with the top bar by thin light strips 9. Secured to said rest piece is a piece 10, in which, and also in the top bar, are formed holes 11 and open-ended slots 12 each hole being adapted to receive the reduced end 13 of a semi-circular loop 14, the other end being formed with a head 15, and being adapted to drop into the corresponding open-ended slot 12. In placing a piece of sheet music in position upon the rack 1 of the music turner, the small end of each loop 14 is

first passed through holes formed in the sheets which should be at this time turned over to the left, and then into one of the holes 11, and then the headed end of said loop is 60 dropped down into the slot 12. All of the leaves are then turned upon said loop from a position on the left of the rack to a position on the right thereof.

Firmly secured to the bottom of the rack 65 1 is a frame 20 which carries the mechanism for turning the sheets. Said frame 20 has, substantially opposite to its point of connection at the bottom of the bar, an upwardly extending pin 21, which can engage 70 any one of a series of holes 22 formed in the ledge of the angular rest piece 8. On account of the flexibility of the rest piece and of the strips 9, the middle of said rest piece can easily be moved in or out to permit said 75 pin to enter any one of said holes, thereby adjusting said rest piece for carrying pieces of music or books of different thicknesses.

Between two plates 23, 24, extending parallel with each other and obliquely upward 80 and to the right, are confined a suitable number, four being here shown, of cup-shaped disks 25, to the periphery of each of which is attached a turning finger 26, said turning fingers extending at an angle of 85 about 45 degrees with the plane of the disk, so that, when said disk is in one position, the turning finger extends upward or parallel with the sides 2 of the rack, and when said disk has turned through an angle of 90 degrees in its own plane, said finger then 90 extends horizontally or parallel to the base of the turner rack. Within each disk is a coiled spring 27, the outer end of which is attached at 28 to the periphery of the disk 95 while the inner end is secured to a shaft 29 passing centrally through all of said disks. Each spring is so disposed that, when the disk is turned so that the corresponding finger is moved from a horizontal to a vertical 100 position, the spring is wound up, and, consequently, if the spring is released the effect of its expansion is to move the finger from a vertical to a horizontal position. Each of said disks has formed in its periphery a notch 30, and when the disks are all in such position that the fingers extend vertically, the said notches are in line with each other at the lowest points of the disks, and in this 105 position they are adapted to be engaged by 110 a key 31 formed upon a slide piece 32, which slides in a suitable bearing in the frame, and

has formed thereon a rack 33. Said rack engages a pinion 34 loosely mounted upon a post 35, around which post is a coiled spring 36, one end of which is attached to the post 5 and the other end is attached to said pinion. To said pinion is secured a ratchet wheel 37, which is adapted to be engaged by the beveled end 38 of a push rod 39 passing through the frame 20 of the mechanism, and normally pressed outward by means of a coiled spring 40 pressed against the head 41 of said push rod.

The operation is therefore as follows: In arranging the sheets of music, as the player 15 turns each sheet to the right, he inserts a turning finger between said sheet and the next sheet to the left. As each turning finger in succession is thus moved from a horizontal to a vertical position, the corresponding 20 disk 25 is moved so that its notch 30 is brought into alignment with the key 31, and as soon as this takes place, said key slides into said notch, being moved to do so by the unwinding of the coiled spring 36 acting 25 through the pinion 34 and rack 33. The sheets having all been placed in position with the turning fingers interposed therebetween, the player plays the piece, and, when he desires to turn over the first sheet, he 30 pushes in the push rod, the effect of which is to rotate the ratchet wheel 37 and the pinion 34, and withdraw the rack 33, so that the sliding key 31 is withdrawn from engagement 35 with the notch in the disk of the first turning arm, so that said disk is free to turn. This it immediately does by reason of the expansive force of the coiled spring 27 within the disk. Consequently, the turning finger is moved from a vertical to a horizontal 40 position, turning the sheet over and laying it on the left. This operation is repeated for each turning finger in succession.

It will be observed that, as the operator pushes in the push rod to turn each sheet in 45 succession, he correspondingly winds up the coiled spring 40 around the post 35, so that, the next time the music turner is used, the energy thus stored up in the coiled spring serves to automatically move the sliding key 50 into successive engagement with the notches and the disks, as the turning fingers are placed in proper or operative relations to the sheets of the music. Consequently no

special winding up is ever required but the device is always ready for use.

To avoid the noise that would be occasioned by the ends of the turning fingers striking a side of the rack 1, I secure upon said side, at the proper position to receive the impact of said ends, a strip of rubber 42, and 60 a piece of metal 43 is also preferably provided, turned up at the lower end to prevent the ends of the turning fingers rebounding out of position.

I claim:—

1. In a device of the character described, the combination of a series of fingers, rotary devices to which said fingers are secured, each rotary device being arranged to rotate about an axis making substantially half a 70 right angle with the corresponding finger, and means for moving said devices, substantially as described.

2. In a device of the character described, the combination of a series of fingers, a series 75 of rotary devices to which said fingers are severally secured, a common shaft for said devices, said fingers being secured to said devices at an angle of substantially half a right angle with said shaft, springs for turning the 80 several devices, and a latch arranged to be operated to release said devices in succession to be actuated by said springs, substantially as described.

3. In a device of the character described, 85 the combination of a series of fingers, a series of rotary devices to which said fingers are severally secured, a common shaft for said devices, said fingers being secured to said devices at an angle of substantially half a right 90 angle with said shaft, springs for turning the several devices, a latch arranged to be operated to release said devices in succession to be actuated by said springs, means for withdrawing said latch, and a spring for projecting said latch into its retaining position, and arranged to be energized by said withdrawal, 95 substantially as described.

In testimony whereof I have hereunto set my hand in the presence of two subscribing 100 witnesses.

JAMES SCHOLTZ.
